UNITED STATES PATENT OFFICE.

HENRY J. ALTMAN, OF NEW YORK, N. Y.

DESIGN FOR A PLAYING-CARD BOX.

SPECIFICATION forming part of Design No. 35,750, dated February 18, 1902.

Application filed October 22, 1901. Serial No. 79,604. Term of patent 3½ years.

To all whom it may concern:

Be it known that I, HENRY J. ALTMAN, a citizen of the United States, residing at No. 277 West One Hundred and Seventeenth street, 5 borough of Manhattan, city, county, and State of New York, have invented and produced a new and original Design for Playing-Card Boxes, of which the following is a specification, reference being had to the accompanying drawing, forming part thereof.

The drawing is a perspective view of my playing-card box, showing my new design and the panels and ornamentation hereinafter referred to.

As shown in the drawing, the leading material feature of my design consists of a series of panels arranged over the surface of the top, upper side, or face of a box to contain playing-cards, as shown in the drawing. The 15 panels are five in number. They consist of three parallel rectangular panels, having a small space between each, set in the top, upper side, or face of the box and running lengthwise on said box, the outer or exterior panels 20 being slightly shorter than the length of the box and having their ends convex, and the

center or middle panel being slightly shorter than the exterior panels and having its ends concave, and at each end of this middle panel and separated from it is placed a small panel, 30 in the form of an isosceles triangle, having its base parallel to the ends of the box and its equal sides concave. About the whole is a border formed by lines drawn to form two concentric rectangles, of which the inner is 35 slightly smaller than the outer and the outer slightly smaller than that formed by the edges of the upper surface of the box. The whole forms a smooth or plane surface.

Having described my invention, what I 40 claim as new, and desire to secure by Letters Patent, is—

The design for a playing-card box as herein shown and described.

In testimony whereof I have signed my 45 name to this specification in the presence of two subscribing witnesses.

H. J. ALTMAN.
